BY T.H. Gibbs.

ATTORNEY.

UNITED STATES PATENT OFFICE.

RALPH G. NICHOLS, OF RICHMOND HILL, NEW YORK, ASSIGNOR TO AMERICAN CAR AND FOUNDRY COMPANY, OF NEW YORK, N. Y., A CORPORATION OF NEW JERSEY.

SELF-DUMPING MINE CAR.

Application filed November 30, 1921. Serial No. 518,891.

To all whom it may concern:

Be it known that I, RALPH G. NICHOLS, residing at Richmond Hill, Queens County, New York, and being a citizen of the United States, have invented certain new and useful Improvements in a Self-Dumping Mine Car, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Fig. 1 is a side elevation of my improved dumping car, the means for automatically opening the doors being shown;

Fig. 2 is a partial plan view of my improved dumping car, some parts being broken away in order to show other parts more clearly;

Fig. 3 is an end elevation, part of the bumper and end sill being broken away in order to show the door locking mechanism;

Fig. 4 is a central vertical section of my improved car with the means for automatically closing the doors shown in side elevation;

Fig. 5 is a section showing the manner of controlling the locking means of one door by another door; and

Fig. 6 is a view partly in section, showing the manner of mounting the doors.

It is the object of my invention to provide an improved automatically operating dumping car having a plurality of dumping doors designed to dump their loads successively upon the operation of the locking means controlling one of the doors. It

is also the object of my invention to so design the dumping doors that they will be locked when closed in the reverse order to dumping and will be kept locked in closed position upon the closing of the door first released and it is also an object of my invention to provide suitable means for automatically opening and closing the doors.

While I have shown my invention applied to a car of the type known as a mine car it is to be understood that my inven-

tion may be applied to cars of other types or designed for other purposes. In the embodiment shown, the car comprises a frame composed of side members 1 and end members 2 carried upon axles 3 to which the wheels 4 are attached and supporting the sides 5, ends 6 and bumpers 7 which may be of any desired construction. The dumping doors 8, 9 and 10, which may, as shown, constitute almost the entire floor of the car and be of any desired number comprise metal plates bent to a concave shape. At one end of each plate are secured bearing brackets 11 having projecting cam-shaped portions 12 adapted to be engaged with the door plate and to define a cam shape for the end of the door plate. Integral with each bearing bracket 11 is a bearing stud 13 that engages in a bearing formed in a metal strap 14 attached to a side member 1 by bolts 15. Along the sides of the doors are secured the angles 16, bent to conform to the shape of the door plates and which serve to reinforce the door plates and to prevent discharge of the contents of the car where, as shown in Fig. 1, the plates dip below the side members 1.

To the free edge of the door 8 there are secured a plurality of projecting lugs 17 adapted, when the door is in closed position, to be engaged by locking mechanisms consisting of lever arms 18 having the arms 19 projecting at right angles thereto and provided with shoulders 20 to engage the lugs 17. The lever arms 18 are pivotally supported on pins 21 supported in openings in the end 6 and a cover plate 22 secured to the end 6. Straps 23 secured to the end 6 serve as guides for the arms 18 which project beyond the sides of the car so as to engage the operating cams 24 mounted at the side of the track. To secure each of the other doors in closed position there is provided a locking plate or member 25 that serves as a part of the car floor and has a portion adapted to be engaged beneath the free end of the door. Each member 25 is pivotally supported by straps 26 which form loops about the axle 3. In the car shown in the drawings, the axles 3 are adjacent the bearing studs 13 and the locking members 25 are positioned so as to be operated by the cam-shaped ends of the door plates carried on the adjacent bearing studs, the locking members 25 and the cam shaped

ends of the door plates being so designed that each locking member 25 is held in locking position, as shown in Fig. 5, when the door that operates it is in closed position 5 and the locking member is released when the door is in open position. Where the arrangement of the doors is such that the axles are not adjacent the points of support for the doors, the locking members 25 will 10 be supported on cross members carried by the side members 1. To prevent the load from interfering with the operation of the locking members, protection plates or angles 15 27 are mounted on the side members 1 directly over the supports for the locking members 25.

To return the doors to closed position a cam member 28, mounted between the rails, is adapted to engage the doors and return 20 each door to the closed position before the following door is operated sufficiently to move the locking member 25 from the release position.

In service, the car will be in motion 25 throughout the operation of opening and closing the doors and will be run with the levers 18 at the rear of the car so that when the levers 18 engage the cams 24, erected at the dumping opening in the track, 30 all the doors of the car will be over the dumping opening. Operation of the levers 18 by the cams 24 will withdraw the shoulders 20 on the arms 19 from the lugs 17 permitting the door 8 to drop. As the 35 door 8 drops, the cam-shaped end of the door plate will be disengaged from the locking member 25 it engages permitting the weight on door 9 to force back the locking member 25 and release the door. This will 40 disengage the cam-shaped end of the door 9 from the locking members 25 in engagement with door 10 which will then be released thus giving a successive operation of the doors that will extend throughout the 45 length of the car.

In closing the doors, the doors are operated in the reverse order, door 10 at the front of the car engaging the cam 28 and being raised to and held in closed position. 50 As the door 9 is raised the cam end of the door plate will engage the locking member 25 and force it to engaging position beneath the door 10, thus locking the door 10 in closed position as the door 9 is held in closed 55 position by the cam 28 until it is locked in closed position by the raising of the door 8. The doors will thus be successively raised to closed position and locked upon the closing of the door following until the last 60 door is raised whereupon lugs 17 will be engaged by the shoulders 20 on the arms 19 and all the doors will be securely fastened until the levers 18 are again operated by the cams 24.

65 What I claim is:

1. In a dumping car, a plurality of dumping doors and a locking means for one of said doors mounted independently of said doors and controlled by the other of said doors. 70

2. In a dumping car, a plurality of dumping doors and a locking means between said doors supported independently of said doors and adapted to be engaged with one of said doors upon the operation of another 75 of said doors.

3. A dumping car comprising a frame, axles supporting said frame, dumping doors pivotally mounted on said frame beneath the axles and locking means for said doors loosely mounted on said axles and controlled by movement of the doors. 80

4. A dumping car comprising a frame, dumping doors carried by said frame and locking means for some of said doors mounted independently of all of said doors for operation by others of said doors. 85

5. In a dumping car, a plurality of dumping doors and a lock for one door independent from the doors and pivotally mounted over the support of a second door and controlled thereby for movement into and out of position for locking engagement with the first door. 90

6. In a dumping car, a frame, axles supporting said frame, bearing brackets secured to said frame, dumping doors pivotally mounted in said bearing brackets and locking means for some of said doors pivotally mounted on said axles and controlled by others of said doors. 100

7. In a dumping car, a pivotally mounted dumping door, a pivotally mounted locking means engaging the free edge of the door and a second pivotally mounted dumping door having a curved portion adjacent its support and adapted to engage the locking means and force it into engagement with said first mentioned dumping door. 105

8. In a dumping car, a pivotally mounted dumping door having a flat free edge, a pivotally mounted locking means having an outwardly bent portion adapted to cooperate with the free edge of said door and a second pivotally mounted dumping door having a curved portion adjacent its support adapted to hold said locking means in engaging position when said second door is in closed position. 110

9. In a dumping car, a dumping door having a flat free edge, a pivotally mounted locking means having a surface adapted to engage the free edge of said door and a second dumping door having a curved portion adjacent its support adapted to operate said locking means. 115

10. In a dumping car, a dumping door, a pivotally mounted locking means having a flat surface adapted to engage the free edge of said door and a second dumping 120 125 130

door having a portion curved about its axis of support and engaging said locking means to hold said locking means in engagement with said first mentioned door.

5 11. In a dumping car, a pivotally mounted dumping door, a pivotally mounted locking means adapted to support the free edge of said door and a second pivotally mounted dumping door having a curved portion 10 adapted to hold said locking means in engagement with said first mentioned door.

12. In a dumping car, a plurality of dumping doors, a locking means suspended between said doors and means on one of 15 said doors engaging said locking means to

force said locking means into engagement with the other of said doors.

13. In a dumping car, a plurality of dumping doors, a locking means suspended between said doors and a curved surface on 20 one of said doors adapted to force said locking means into engagement with the free edge of the other of said doors.

In witness whereof I have hereunto set my hand in the presence of two witnesses.

RALPH G. NICHOLS.
